DRIVING MECHANISM FOR HAIR CLIPPERS

Henry E. Meltzer, Racine, Wis., assignor to All-Over Manufacturing Co., Racine, Wis.

Application November 23, 1946, Serial No. 711,929

1 Claim. (Cl. 30—210)

1

This invention appertains to electrically operated clippers, dry shavers and the like and more particularly to an improved driving mechanism between the motor and the movable blade.

One of the primary objects of my invention is to provide a novel operating lever actuating the movable blade, whereby not only will a silent drive be had, but whereby wear between the lever and the movable blade can be readily taken care of.

In hair clippers and the like, due to the rapid oscillation of the operating lever, there is a constant rubbing and wearing action between the movable blade and the operating lever and consequently, in the course of time, an objectional play and lost motion takes place between the blade or lever.

Another salient object of my invention is to provide a simple and convenient means for adjusting the active width of the driving end of said lever for effectively taking up any loose play between the lever and the movable blade.

A further object of my invention is to provide a driving lever with a longitudinal slit and means operable in said slit including an adjusting screw for spreading the lever on each side of the slit for taking up any wear between the blade and lever.

A further important object of my invention is the provision of means for bracing the lever and for holding the screw in an adjusted position and against accidental loss.

A still further object of my invention is to provide means for forming the driving end of the lever from composition material whereby to reduce objectional noise between the lever and blade.

A still further important object of my invention is to provide a guide plate secured to the movable blade for receiving the driving end of the lever, the guide plate having means for guiding the lever into driving engagement with the blade and down turned lips embodying oppositely disposed smooth bearing surfaces against which the lever is adapted to bear.

With these and other objects in view the invention consists in the novel construction, arrangement and formation of parts, as will be hereinafter more specifically described, claimed, and illustrated in the accompanying drawing, in which drawing:

Figure 1 is a fragmentary top plan view showing the forward end of my improved clipper with the upper half of the case of the clipper removed

Figure 2 is a fragmentary longitudinal sec-

2

tional view of the clipper taken substantially on the line 2—2 of Figure 1 looking in the direction of the arrows.

Figure 3 is an enlarged detailed perspective view of the guide plate carried by the movable blade.

Figure 4 is a fragmentary top plan view illustrating my novel driving lever, parts of the figure being shown broken away and in section.

10 Figure 5 is a detail longitudinal sectional view through the driving lever taken substantially on the line 5—5 of Figure 4 looking in the direction of the arrows.

15 Figure 6 is an enlarged detail transverse sectional view through the driving lever taken substantially on the line 6—6 of Figure 5 looking in the direction of the arrows.

Figure 7 is a similar sectional view being taken on the line 7—7 of Figure 6 looking in the direction of the arrows.

20 Figure 8 is a view similar to Figures 6 and 7, but taken on the line 8—8 of Figure 5 looking in the direction of the arrows, illustrating the adjusting screw.

25 Referring to the drawing in detail, wherein similar reference characters designate corresponding parts throughout the several views the letter C generally indicates by improved clipper and the same includes a casing or housing 10

30 for enclosing the operating mechanism. This casing or housing 10 can take any preferred form and includes a lower section 11 and an upper removable section 12. The forward end of the housing 10 receives, supports and carries in any

35 desired way the cutting assembly 13 and this assembly includes a lower stationary cutting blade or comb plate 14 and an upper movable cutting blade 15. The cutting blade 15 is movable back and forth over the stationary blade by means, which will be later set forth.

40 The operating mechanism can include an electric motor of any desired type, and as illustrated the same may consist of an alternating current motor 16 and its armature 17. The construction

45 and type of the motor does not enter into the present invention and can be of the type found in many clippers on the market.

46 As illustrated, the forward end of the armature 17 has connected therewith the drive lever 18 for the movable blade and the construction of this drive lever forms an important part of my present invention.

47 As illustrated, the driving lever 18 can include 50 a relatively thin forwarding projecting plate or

arm 19 which is securely fastened at one edge to the armature 17 for movement therewith.

Fastened on the upper surface of the plate or arm 19 is a relatively thick driving arm 20 which is preferably formed from composition material, so as to reduce noise incident to its driving the movable blade 15. It is to be noted that the forward end of the arm 20 is enlarged laterally to provide arcuate driving faces 21. The arm is provided with a centrally disposed longitudinally extending slot or slit 22 and this slit opens out through the forward end of the arm and terminates short of the rear end of the arm. As illustrated, the rear end of the arm is also preferably increased in width and is secured to the plate 19 by rivets 23.

I provide means for spreading the forward end of the arm 20 on each side of the slot or slit 22 and this means includes a screw 24 which is threaded into the plate 19. The screw 24 extends through the slit or slot 22 and is provided with a cone head 25. Obviously by turning the screw down, the cone shaped head functions as a wedge for spreading the arm in opposite directions on each side of the slit. Obviously by adjusting the screw, the desired width of the forward end of the arm can be had.

In order to brace the arm 20 I provide a reinforcing plate 26. This plate 26 can be of an inverted U shape in cross section and embraces the top and side portions of the arm 20. Particular attention is invited to the fact, however, that the side portions of the reinforcing plate 26 terminate materially short of the forward end of the arm 20, so that spreading of the forward end of the arm is permitted. The front end of the plate engages over the top of the adjusting screw 24 and holds the adjusting screw in place against turning. The plate 26 can be held tightly down on the arm and against the screw by means of a holding machine screw 27. This screw also extends through the slot or slit 22 and is threaded into the plate 24.

As is common in blade assemblies, the movable blade 14 is provided with a notch 28 in its rear edge for receiving the driving end of the arm 20 and secured to the movable blade 15 is a guide plate 29. This guide plate 29 is likewise provided with a central notch for the driving end of the arm and the forward edges of the notch are outwardly turned to provide wide flaring guide lips 30. These lips serve as means of guiding the forward driving end of the arm in place during the removal and placing of the blade assembly in position on the casing 10. In the formation of the notch in the guide plate 29, the side edges thereof in rear of the guide lips 30, in spite of machining, are often left with rough surfaces which act in the nature of files. In accordance with my inven-

tion the side edges of the notch, forward of the guide lips 30 are provided with down turned spaced parallel driving tongues 31. These tongues give a smooth wearing surface against which the drive end of the arm engages. The plate 29 can be riveted or otherwise fastened to the movable blade 15 and as the blade, in the present instance is operated from an alternating current motor the blade is preferably supported and centered by resilient arms 32. These arms can be secured to the movable blade 15 by the same rivets for holding the guide plate 29 in position. In operation of the clipper the driving end of the arm is received within the notch of the movable blade and the guide plate 29 and if wear occurs between the drive arm and the lips 31, it is merely necessary to remove the guard and brace plate 26 and adjust the screw 24 until the arm again engages the lips with the proper tension.

Changes in details may be made without departing from the spirit or the scope of my invention, but what I claim as new is:

In hair clippers, a lever for operating the movable blade of a clipper blade assembly including an arm having side arcuate driving faces and a longitudinally extending slot between the driving faces and opening out at the forward end of the arm, and terminating short of the rear end of the arm, means operable in said slot for spreading the forward end of the arm and the driving faces away from one another including a screw adjustable into and out of the slot having a cone shaped spreading head, and a reinforcing plate for said arm detachably connected thereto for engaging the head of the screw to hold the same in an adjusted position, and said reinforcing plate having side flanges engaging the opposite sides of the arm in rear of said driving faces.

HENRY E. MELTZER.
